CLAIM

The ornamental design for a biometric hub with handles, as shown and described.

DESCRIPTION

FIG. 1 is a left front perspective view of a biometric hub with handles in accordance with the present invention; FIG. 2 is a front view of the biometric hub with handles of FIG. 1;

FIG. 3 is a back view of the biometric hub with handles of FIG. 1;

FIG. 4 is a left side view of the biometric hub with handles of FIG. 1;

FIG. 5 is a right side view of the biometric hub with handles of FIG. 1;

FIG. 6 is a top view of the biometric hub with handles of FIG. 1; and,

FIG. 7 is a bottom view of the biometric hub with handles of FIG. 1.

The broken lines in the drawings depict portions of the biometric hub with handles or the environment in which the biometric hub with handles is located that form no part of the claimed design.
